UNITED STATES PATENT OFFICE.

HENRY F. WOODMANY, OF WHITINSVILLE, MASSACHUSETTS; CYRUS A. TAFT EXECUTOR OF SAID WOODMANY, DECEASED.

SPINNING AND TWISTING MACHINE SPINDLE.

SPECIFICATION forming part of Letters Patent No. 643,343, dated February 13, 1900.

Application filed October 13, 1898. Serial No. 693,450. (No model.)

To all whom it may concern:

Be it known that I, HENRY F. WOODMANY, of Whitinsville, in the county of Worcester and State of Massachusetts, have invented a new and useful Improvement in Spinning and Twisting Machine Spindles; and I hereby declare that the following is a full, clear, and exact description of the same, reference being had to the accompanying drawings, forming part of this specification.

This invention has reference to an improvement in spinning and twisting machine spindles in which the spindle and the driving-whirl are disconnected and may rotate one independent of the other, of which, as far as I know, I am the original inventor.

The object of my present invention is to facilitate the independent automatic adjustment of the spindle and the driving-whirl and economize power.

The invention consists in the peculiar and novel construction by which the spindle and the tube forming the support for the driving-whirl rest on a series of balls, whereby the foot of the spindle and the foot of the whirl-supporting tube may move laterally through a limited distance and rotate on the supporting-balls.

Figure 1 is a vertical sectional view of my improved spindle, showing the same provided with a bobbin. Fig. 2 is a side view, and Fig. 3 a sectional view, of the bolster. Fig. 4 is a side view, and Fig. 5 a sectional view, of a tube secured to and forming the support of the sleeve-whirl. Fig. 6 is a side view of the lower part of the spindle. Fig. 7 is a transverse sectional view of the bolster-case immediately above the enlarged foot of the spindle. Fig. 8 is a sectional view of the sleeve-whirl.

Similar marks of reference indicate corresponding parts in all the figures.

In the drawings, *a* indicates the bolster-case, which may be of any one of the usual types adapted to be secured to the bolster-rail of the machine. In the preferred form shown in the drawings the bolster-case is provided with the annular flange *a'* by which it rests on the bolster-rail, with the nut *a''* on the lower screw-threaded portion by which it is secured to the bolster-rail, and with the laterally-ex-

tending oil-duct *a''*, on the upward extension of which the doffer-guard or holddown *a'* is pivoted. The bolster-case is bored out to receive the bolster *a''*, which fits the same with a sliding fit and is provided with a spline *a''* or projection which enters a groove in the bolster-case, so as to hold the bolster against rotation. A steel plug is driven into the bolster-case to form the step-bearing *a''*.

The sleeve-whirl *b* is provided at its upper end with the slightly-conical hole *b'* and at its lower end with the whirl *b''* and preferably with the cup *b'''*, which forms a socket for the reception of the lower end of the bobbin. The tube *b''* has a slightly-tapering upper end *b''*, which when driven into the tapering hole *b'* in the sleeve-whirl *b* firmly secures the tube *b''* in the sleeve-whirl. The bearings *b''* and *b'''* on the tube *b''* fit the interior of the bolster *a''* with a loose sliding fit.

The lower end of the spindle *c* is provided with the cylindrical enlargement *c'*, and at the junction of the spindle *c* with the enlargement *c'* the concave bearing-groove *c''* forms the race for the series of balls *c'''*. The foot of the spindle *c''* is supported on the series of balls *c'''*, and the spindle *c* extends through the tube *b''* and may freely rotate in the same, having sufficient freedom to permit of the lateral motion in all directions required to yield to an unbalanced load. The blade *c''* of the spindle supports the upper end of the bobbin *d*, the lower end of which is supported on the sleeve-whirl *b*, which is vertically supported by the tube *b''*, resting on the series of balls *c'''*. As the tube *b''* is sufficiently loose in the bolster *a''* to permit of automatic lateral adjustment the foot of the tube may move laterally on the balls *c'''*. By this construction the spindle may rotate independently of or with the sleeve-whirl. With the upper end of the bobbin *d* in adhesive frictional contact with the blade *c''* of the spindle, the spindle and the sleeve-whirl will rotate together, being connected by means of the bobbin. When the bobbin is removed, the sleeve-whirl continues to rotate, being driven by the driving-band, and the spindle will remain stationary or creep around by occasional contact with the tube *b''*.

Having thus described my invention, I

claim as new and desire to secure by Letters Patent—

1. In a spinning or twisting machine spindle, the combination with a sleeve-whirl having a supporting-tube inclosing the spindle but loose on the same and the live-spindle, of the series of balls c^3 forming the vertical support of the sleeve-whirl and the series of balls c^5 forming the vertical support of the spindle, as described.
2. In a spinning or twisting machine spindle, the combination with the bolster-case a , the bolster a^6 secured in the bolster-case against rotation and the step a^7 of the live-spindle c having the cylindrical enlargement c^1 , the groove c^2 and the conical foot c^4 , the sleeve-whirl b having the tube b^4 secured thereto, and the series of balls c^3 and c^5 forming the vertical support of the sleeve-whirl and of the spindle; whereby the sleeve-whirl

may rotate independent of or with the spindle supported on the ball-bearing, as described.

3. In a bobbin-support, in combination, a bolster-case, a live-spindle rotatably supported in the bolster-case, an annular groove in the spindle adapted to form the race for a ball-bearing, a sleeve-whirl having a supporting-tube inclosing the spindle but loose on the same and a series of balls in the annular groove of the spindle; whereby the sleeve-whirl is vertically supported on the balls and may turn on the spindle, as described.

In witness whereof I have hereunto set my hand.

HENRY F. WOODMANY.
